DESIGN FOR A TOE CAP FOR SKATES

Esther L. Burns, Colorado Springs, Colo.

Application July 25, 1940, Serial No. 93,930

Term of patent 7 years

To all whom it may concern:

Be it known that I, Esther L. Burns, a citizen of the United States, residing at Colorado Springs, in the county of El Paso and State of Colorado, have invented a new, original, and ornamental Design for Toe Cap for Skates, of which the following is a specification, reference being had to the accompanying drawing, forming part thereof, in which:

Figure 1 is a side view in elevation of a toe cap for skates, showing my new design, Figure 2 is a top plan view of the same, and Figure 3 is a front view in elevation.

I claim:

The ornamental design for a toe cap for skates, as shown.

ESTHER L. BURNS.
